INVENTOR:

Louis Loret-Fleurance

BY

June Daniels, Jr.

ATTORNEY

UNITED STATES PATENT OFFICE.

LOUIS LORET-FLEURANCE, OF ANGERS, FRANCE.

SAFTY-RAZOR GUARD.

Application filed May 8, 1922. Serial No. 559,298.

To all whom it may concern:

Be it known that I, LOUIS LORET-FLEURANCE, a citizen of the Republic of France, and resident of Angers, France (post-office address 7 Rue des Poeliers), have invented a new and useful Safety-Razor Guard, which improvements are fully set forth in the following specification.

The object of my invention is a guard for safety razors permitting, due to its characteristic features, shaving with any flat or hollow bladed safety razor with great comfort and ease.

An embodiment of the invention is illustrated as an example by the appended drawing, wherein:

Figure 1 is an inverted perspective view of the guard,

Figure 2 is an end view of Figure 1.

Figure 3 is a perspective view looking toward the top of the guard.

Figure 4 is a side elevation of a safety razor handle equipped with the guard.

The guard which is the object of my invention is essentially characterized by the fact that its teeth, indentations or guides 1 are arranged slantwise, an arrangement which permits shaving without any difficulty even the most awkward growth of a beard.

On the other hand, the indentations, teeth or guides 1 are reversed and leave a space 2 between their ends and the adjacent edge of the blade sufficient to allow the bristles and the soap to be cleared off. It will be observed, in this connection, that the teeth 1, instead of being formed immediately at the edges of the guard plate, are formed along the outer edges of a pair of longitudinal slots 3 which are located wholly within the confines of the guard and terminate in proximity to the ends thereof. These slots are disposed parallel with, and close to, the edges of the guard plate; and the teeth 1 extend inwardly toward, but terminate short of, the inner edges of the slots in order to provide the space 2 previously mentioned.

The edges of the guard plate may, however, be indented, as indicated at 4.

Of course, the guard may be made either concave-convex or flat, with or without a stem, according to the kind of razor to which it is to be adapted. The slant of the teeth may be in either direction, according as the razor is to be operated by a right-handed or by a left-handed user.

Having now particularly described and ascertained the nature of my said invention and the manner in which the same is to be performed, I declare that what I claim is:

1. A guard plate for safety razors, formed adjacent to and parallel with each longitudinal edge with a relatively narrow longitudinal slot, the inner longitudinal edge of which is straight and the ends of which terminate in proximity to the ends of the plate; and a series of guard teeth projecting inwardly from the outer longitudinal edge of each slot toward the said inner longitudinal edge thereof, the teeth of each series terminating short of the corresponding inner longitudinal edge to provide a clearance space for hair and soap. 60

2. A guard plate for safety razors, formed adjacent to and parallel with each longitudinal edge with a relatively narrow longitudinal slot, the inner longitudinal edge of which is straight and the ends of which terminate in proximity to the ends of the plate; and a series of guard teeth projecting inwardly from the outer longitudinal edge of each slot toward the said inner longitudinal edge thereof, the teeth of each series extending at an incline relatively to the axis of the respective slot and terminating short of the inner edge thereof to provide a clearance space for hair and soap. 75

3. A guard plate for safety razors, formed adjacent to and parallel with each longitudinal edge with a relatively-narrow longitudinal slot, the inner longitudinal edge of which is straight and the ends of which terminate in proximity to the ends of the plate; and a series of guard teeth projecting inwardly from the outer longitudinal edge of each slot toward the said inner longitudinal edge thereof, the teeth of each series terminating short of the corresponding inner longitudinal edge to provide a clearance space for hair and soap; each edge of the guard plate being indented and slightly bowed. 90

4. A guard plate for safety razors, formed adjacent to and parallel with each longitudinal edge with a relatively-narrow longitudinal slot, the inner longitudinal edge of which is straight and the ends of which terminate in proximity to the ends of the plate; and a series of guard teeth projecting inwardly from the outer longitudinal edge of each slot toward the said 105

inner longitudinal edge thereof, the teeth of each series extending at an incline relatively to the axis of the respective slot and terminating short of the corresponding inner longitudinal edge to provide a clearance space for hair and soap; each edge of the guard plate being indented and slightly bowed.

In testimony whereof I have signed this specification in the presence of two subscribing witnesses.

LOUIS LORET-FLEURANCE.
